UNITED STATES PATENT OFFICE.

JOHN M. SARGEANT, OF ELMIRA, NEW YORK.

BROODER HEATER.

Application filed February 7, 1924. Serial No. 691,232.

To all whom it may concern:

Be it known that I, JOHN M. SARGEANT, a citizen of the United States, residing at Elmira, in the county of Chemung and State 60 of New York, have invented certain new and useful Improvements in Brooder Heaters, of which the following is a specification, reference being had to the accompanying drawings.

10 This invention relates to an improved heater for use in connection with a brooder in which small chickens are kept until large enough to be let out in the open, and one object of the invention is to provide a heater 15 which is so constructed that it also forms a cover and will cause the hot air to be directed downwardly upon the small chickens when they are standing beneath the hover-forming portion about the heater.

20 Another object of the invention is to provide a heater which is so constructed that the warm air entering the brooder through the heater may be directed downwardly upon the floor of the brooder thereby preventing 25 cold air from accumulating upon the floor.

Another object of the invention is to so 30 construct this heater that fresh air may be drawn into the body of the heater so that the lamp will burn properly and so that a supply of fresh and warm air may be supplied to the interior of the brooder and thereby keep the air in the brooder from becoming stale.

35 Another object of the invention is to so construct this heater that it may be securely fastened to the floor of the brooder with a portion of the heater beneath the floor and a portion above the floor within the brooder.

40 Another object of the invention is to so construct this heater that when in place the lamp may be drawn upwardly from the oil reservoir through the heating drum or body of the heater and the oil reservoir filled with oil by means of a funnel passed 45 downwardly through the air drum thereby making it unnecessary to lift the brooder and remove the oil reservoir in order to permit the reservoir to be refilled with oil.

50 Another object of the invention is to provide improved means for mounting the lamp so that it may be easily removed and to so mount the lamp holder that when in place the lamp will be properly positioned and the wick of the lamp viewed through a sight 55 opening provided in the air heating drum.

Another object of the invention is to so

construct this heater that any oil which may drip from the wick as the lamp is withdrawn may drain back into the oil reservoir.

Another object of the invention is to so construct this heater that an improved valve may be provided to control the passage of fresh air into the drum and thereby permit the flow of air into the body of the 65 brooder to be controlled.

This invention is illustrated in the accompanying drawings, wherein:—

Figure 1 is a vertical sectional view 70 through the brooder heater.

Figure 2 is a view taken at right angles to the view shown in Figure 1 and showing the brooder heater partially in side elevation and partially in section.

Figure 3 is a transverse sectional view 75 taken along line 3—3 of Figure 2.

This improved heater is for use in connection with a brooder which may be of any conventional construction and, in fact, may simply consist of an ordinary packing box. 80 This brooder has its bottom 1 provided with an opening 2 so that the heater may be put in place and extend through the opening 2 thereby positioning the heater partially within the body of the brooder and partially 85 beneath the bottom or floor of the brooder.

This heater is provided with a hollow body or drum 3 which extends through the opening 2 and is provided with a collar 4 which will be secured to the undersurface of the floor 1 by nails or other suitable fasteners so that the heater will be firmly secured to the floor and will be suspended from the floor of the brooder. The lower portion 90 of this drum is provided with a concaved or tapered bottom 5 which terminates in a threaded neck 6 which extends downwardly below the lower end of the drum and is intended to be screwed into the upwardly 95 extending neck 7 of the oil reservoir 8. The necks 6 and 7 are of such length that when the neck 6 is screwed tightly into the neck 7 the lower edge of the drum 3 will fit tightly against the upper wall of the reservoir 100 8. It will therefore be seen that by means of the tapered bottom 5 any oil which may drip from the wick as the lamp is withdrawn may be guided back into the reservoir 105 by this tapered bottom and neck 6.

Openings 9 are provided in the drum above the bottom 5 so that air may enter

the drum to supply the necessary oxygen to the lamp. This drum is to serve as a conveyor for air and there has, therefore, been provided an inner annular wall 10 which is positioned in spaced relation to the wall of the drum and provided at its upper and lower ends with collars 11 and 12 extending from the inner wall 10 to the wall 3 of the drum and thereby providing an air space 13 closed at its upper and lower ends. Openings 14 are provided in the drum 3 adjacent the lower end of the air space 13 so that air may enter this space beneath the floor of the brooder, and openings 15 are provided in the upper end portion of the wall 10 so that the air after passing upwardly through this air space 13 may pass through these openings 15 and then upwardly to a point above the wall 10 and out into the brooder through the outlet openings 16. A removable cap 17 has been provided for closing the upper end of the drum and causing warm air to pass out through these openings 16 beneath the hover 18. This hover 18 is in the form of a disc secured about the upper end portion of the drum 3 and curved to slope downwardly towards its periphery and therefore cause the warm air to be directed downwardly towards the floor and upon the backs of the small chickens gathered about the drum beneath the hover. A valve ring 19, which is provided with openings 20, is rotatably mounted about the portion of the drum 3 having the openings 14 formed therein so that by proper adjustment of the ring 19 which forms a valve or damper, the openings 20 thereof may be moved into and out of registry with the openings 14 and the amount of fresh air passing into the air space 13 controlled.

A lamp 21 which is used in connection with this heater is of an oil-burning type and is provided with a base including a collar 22 having openings 23 formed therein so that the air passing through the openings 9 into the lower end portion of the drum may feed through these openings 23 and provide the necessary oxygen for proper burning of the lamp. This collar carries the usual chimney 24 which may be formed of glass so that when the lamp is in place the person having charge of the brooder may look through the opening 18 at the mirror 36 mounted in operative relation to the aligned sight openings 25 and 25^a provided in the walls 3 and 10 of the heater and readily see if the lamp is burning properly. The lower end of the lamp base fits loosely in the neck 6 extending from the bottom 5 of the drum and the wick 26 extends through the neck 6 and 7 into the oil reservoir 8. This lamp is not permanently connected with the neck of the heater but fits loosely in it and, therefore,

can be easily lifted upwardly out of the heater through the open upper end of the drum when the cover 17 is removed. In order to permit the lamp to be easily removed or put in place and further to permit of its being properly held in place when in use, there has been provided a hanger or bracket 27 which is formed of wire bent to provide a lower cross arm 28 and upwardly extending arms 29 and 30. The arm 29 is turned inwardly, as shown at 31, and engaged with the collar 22 of the lamp and the arm 30 extends upwardly and is of such length that when the lamp is in place the arm 30 will extend upwardly above the wall 10 so that an eye or head 32 provided at its upper free end may be easily gripped in order to draw the bracket and lamp upwardly out of the heater. Vertically disposed guide strips 33 and 34 are provided at opposite sides of the inner wall 10 so that when the lamp and bracket are put in place the arms 29 and 30 of the bracket may fit between the guide strips which will serve to guide the sliding movement of the bracket to retain the lamp in the proper position when put in place and prevent it from tilting transversely. Therefore, the lamp cannot fall over and either go out or possibly cause a fire which would destroy the brooder and small chickens.

When this heater is to be used, the drum 3 is passed upwardly through the opening 2 provided in the floor of the brooder and the fasteners are then passed through the collar 4 to securely hold the drum in place. The oil reservoir can then be screwed into engagement with the neck 6 of the drum and the hover 18 put in place. The oil may be supplied to the reservoir before it is put in place or a funnel having a long spout may be passed downwardly through the annular wall or drum 10 and the oil poured through this funnel so that it passes through the neck 6 into the reservoir. This last method of filling the reservoir will be employed after the heater has been installed and the reservoir requires re-filling. After the reservoir is full, the lamp together with its bracket 27 will be put in place, the lamp being first lighted and the arms of the bracket will fit between strips 33 and 34 so that this bracket and the lamp carried thereby will be properly positioned. The chimney of this lamp may be of transparent material or may be formed of metal and provided with an opening 35 which will be aligned with the openings 25 and 25^a so that the burning wick may be reflected into the mirror through the aligned openings and viewed through the opening 37. After the lamp has been put in place and is burning properly the cover 17 will be put in place and the brooder is ready for use.

During operation of this heater the air

- which is to supply oxygen to the lamp passes inwardly through the openings 9 and passes into the collar 22 of the lamp through the openings 23 thereof. The heat 5 from this lamp serves to thoroughly heat the inner wall 10 and the air which enters the air space 13 through the openings 14 will pass upwardly about this inner wall and become thoroughly heated. This air, 10 when it reaches the upper end of the air space, passes through the openings 15 directly into the interior of the drum 3 above the upper end portion of the lamp chimney 24 so that it mixes with the very hot air 15 passing out of the upper end of the chimney. This air passes upwardly in the drum 3 after passing through the openings 15 and accumulates in the top of the drum and passes outwardly through the openings 20 16 formed about the upper end portion of the drum. This air which passes through the openings 16 passes out of the heater below the hover 18 and since the hover extends at a downward incline towards its 25 periphery, the warm air will be directed downwardly towards the floor of the brooder so that it will be thrown down upon the backs of small chickens gathered about the heater below the hover and will keep them from 30 becoming cold. It should be further noted that since this warm air is directed downwardly by the hover it will be thrown downwardly upon the floor of the brooder and will serve to drive away any cold air 35 attempting to accumulate in the bottom of the brooder. Therefore, the bottom of the brooder will be kept warm and the small chickens prevented from being chilled. This air moves through the brooder and out 40 through the upper end thereof and therefore a supply of fresh air is constantly passing through the brooder so that stale air is prevented from accumulating in the brooder.
- 45 What is claimed is:—
1. A brooder heater comprising a drum having inner and outer annular walls, the inner wall terminating in spaced relation to the ends of the outer wall and having flanges extending to the outer wall and providing heads for an air chamber between the walls, the outer wall having air inlet openings communicating with the lower end portion of the air chamber and outlet open- 50 ings above the air chamber, the inner wall 55 having air outlet openings communicating with the upper end portion of the air chamber, a hover positioned about the upper end of the outer wall for directing air passing through the outlet openings thereof downwardly, a cover for the upper end of the drum, and heating means in the drum. 60
  2. The structure of claim 1 having the outer wall of the drum provided with a concaved bottom adjacent its lower end and terminating in a depending neck, a fuel reservoir fitting against the lower end of the outer wall and provided with a neck removably engaged with the neck of said bottom, the heating means consisting of 70 a lamp having a base extending into the necks and a wick extending through the necks into the reservoir, the outer wall being provided with air inlets below the air chamber. 75
  3. The structure of claim 1 having the heating means consisting of a lamp in the drum, the walls of the drum being provided with aligned openings for permitting viewing of the burning lamp. 80
  4. The structure of claim 1 having the heating means consisting of a lamp in the drum, the walls of the drum being provided with aligned openings for permitting viewing of the burning lamp, a reflector mounted externally of the drum in operative relation to the aligned sight openings, and a hover upon the upper end portion of the drum having a sight opening therein above 85 said reflector. 90
  5. A brooder heater comprising a drum open at its upper end, a hover having a central opening receiving the upper end of the drum, a removable closure for the open end of the drum, guides extending vertically in the drum and comprising strips disposed vertically in the drum at opposite sides thereof, a bracket moved into and out of the drum through the upper end of the drum and substantially L-shaped in form 100 having its forwardly extending arms slidably engaged with the guide strips and the longer arm extending to a point adjacent the upper end of the drum, and a heater carried by said bracket. 105
- In testimony whereof I hereunto affix my signature.

JOHN M. SARGEANT.
